UNITED STATES PATENT OFFICE.

MERLE PEABODY CHAPLIN, OF WHITE PLAINS, NEW YORK, ASSIGNOR TO WESTERN ELECTRIC COMPANY, INCORPORATED, OF NEW YORK, N. Y., A CORPORATION OF NEW YORK.

TRANSLATING DEVICE.

Application filed October 31, 1921. Serial No. 511,785.

To all whom it may concern:

Be it known that I, MERLE PEABODY CHAPLIN, a citizen of the United States, residing at White Plains, in the county of Westchester, State of New York, have invented certain new and useful Improvements in Translating Devices, of which the following is a full, clear, concise, and exact description.

10 This invention relates to apparatus for translating current impulses into mechanical movements. It is particularly applicable for use in printing telegraph systems, although it may be used for the remote control of 15 power switches, linotype machines and the like.

An object of the invention is to provide positive means for distributing and storing code combinations of signaling impulses and 20 translating the impulses into mechanical movements.

Another object is to provide distributing, storing, and translating means, requiring a minimum number of electrical parts.

25 The application in general comprises a plurality of members, each of which is adapted to occupy either of two positions, depending upon the character of the respective signals. The members, when operated, 30 may control local circuits or actuate work members, as desired.

Referring to the drawings:

Fig. 1 is a side elevation illustrating one embodiment of the invention;

35 Fig. 2 is a plan view of the mechanism shown in Fig. 1.

Figs. 3 and 4 are end views showing the two operating positions of a transfer switch;

Fig. 5 is a view along the line 5-5 of 40 Fig. 1;

Fig. 6 is a top plan of the portion of the distributor shown in Fig. 5;

Fig. 7 illustrates the manner of deflecting the vanes to their two operating positions;

45 Fig. 8 illustrates means for releasing the power shaft of the receiving printer;

Fig. 9 illustrates the various parts of the distributor diagrammatically;

Fig. 10 is a circuit illustrating the connections at a terminal station.

The invention in general comprises an operating unit B, which has power communicated thereto from a continuously rotating motor 5 through an electromagnetic releasing unit A. Both of the units A and B are

mounted on a common base 6, and form a unitary structure.

The releasing unit A comprises among other parts a revolvable shaft 7 extending in a longitudinal plane and supported by means of bearings formed in the uprights 8 and 9 secured to the base 6. Rotatable by friction with the shaft 7 is a stop arm 12 which is rigidly secured to a sleeve 10 connecting discs or cams 19 and 23. The stop arm 12 and the cams 19 and 23 are normally held against rotation by means of a latch 15 under the control of release magnet 16 for periodically allowing the stop arm and the associated cams to be revolved by means of discs of friction material 11 and 18, the disc 11 being held by a metal disc 4 while the disc 18 is positioned by a gear wheel 17. A nut on the end of the shaft 7 compresses a spring 21 against gear wheel 17 which is secured to the shaft 7 by means of a sliding key. Pressure on the gear 17 grips cams 19 and 23, the latter of which is on the left of stop arm 12 and is in engagement with the friction disc 11, between friction discs 11 and 18, both of which are being continuously rotated with the shaft 7. Continuously in engagement with the gear wheel 17 is a pinion 22 which is secured to the shaft of the operating motor 5.

The latch 15 for arresting the stop arm 12 once for each revolution thereof is bell crank shaped, and is provided with a mechanical lock and a mechanically operated means for restoring the same to its locked position just prior to completion of the cycle of rotation by the stop arm 12. For locking the latch 15 in position a horizontally extending member 38 having a notch formed in the free end thereof, and which is held in operative relation with the portion 40 of the bell crank lever by a coiled spring 71, is pivoted to the frame holding the release magnet 16. Thus when the armature 37 of the release magnet 16 is attracted, the member 38 will be lifted out of engagement with portion 40 and thereby unlock the latch 15. Further travel of armature 37 rotates the bell crank lever and positively the latch 15 out of the path of the stop arm 12 which will then be free to rotate. Just prior to the completion of the cycle of rotation by the stop arm 12, the pivoted member 41 is operated by the stop arm, whereby the bell crank lever is rotated so that the notch on 110

the member 38 engages the portion 40 of this bell crank lever and positions the latch 15 in the path of the stop arm 12 for arresting the rotation thereof.

5 Disposed to the left of the stop arm 12 is the circular disc or cam 23 having a link 24 normally in engagement therewith, which serves to effect the rotation of its associated rod 25 through a small angle. This link is 10 rigidly secured to the operating rod 25 which serves to move a stop arm 26 upon the movement of link 24 by the cam 23 into the path of an arm 27 forming a part of the operating unit B, as will be more clearly described 15 hereinafter. For rotating the operating rod 25 in a direction opposite to that caused by the movement of the link 24 to thereby restore this rod and the stop arm 26 to normal, another link 28 is provided, which in 20 turn is operated by the cam 19.

In order to transfer the line circuit from the release control magnet 16 to a pair of operating magnets 29 and 30, also forming a part of the operating unit B, a transfer 25 switch 32, as shown in Figs. 3 and 4, is provided. The transfer switch comprises a pair of oppositely disposed contact arms 33 and 34, which are insulated from one another by means of insulation material 35 30 and are secured in place by an L-shaped member 36 secured to the base 6. Arranged to be moved between the contacts 33 and 34 is a spring operated member 39 carrying contact points for engaging those secured to 35 the members 33 and 34. For operating the member 39 following the energization of the release control magnet 16, an operating link 42 rigidly secured to a shaft 43 is provided, and which is in operative to the irregular-shaped disc 19. Therefore, upon 40 rotation of the disc 19 and the shaft 7 with which it is revoluble through the friction discs 11 and 18, the operating link 42 is moved a distance sufficient to cause rotation 45 of the operating rod 43 through a small angle, and consequently actuation of the contact making member 39 of the transfer switch 32. In this manner the line circuit will be transferred from the windings of the release control magnet 16 to the operating 50 magnets 29 and 30, which will be energized, depending upon the character of the incoming signaling current impulses. Immediately following the reception of the last impulse by either of the operating magnets 29 and 30, an operating link 44, operating in conjunction with the cam 23, transfers the line circuit from the operating magnets 29 and 30 back to the release control magnet 16. 55 The operating unit B comprises a shaft 46 extending between a pair of uprights 47 and 48, and operatively connected with the shaft 7 through a friction clutch, which consists of a pair of circular discs 49 and 50, rigidly secured to the shaft 7. Equally

spaced about the circumference of the discs 49 and 50 and attached thereto are a plurality of posts 51, to which there is secured an irregular-shaped metal disc 52. Disposed on each side of the metal disc 52 are metal plates 53 and 54 which are rigidly secured to the shaft 46 and have on each side thereof discs of friction material continuously rotating with the shaft 7. In order to secure good contact pressure between the plates 49 and 50, and the discs of friction material, a plurality of coiled springs 55 are provided. 70

Spaced equal distances along the shaft 46 and at different angles from a longitudinal plane are a plurality of operating vanes 56, 57, 58, 59 and 60, which have on the free end thereof knife-like projections 70. The vanes 56 to 60 inclusive serve to effect movement of bifurcated members individual thereto, which causes the opening and closure of the electrical circuits extending to the selecting magnets of a receiving printer or effects mechanical positions or selections. 75

Rigidly secured to the uprights 47 and 48 is an irregular-shaped member 61 to 90 which the bifurcated members 63, 64, 65, 66 and 67, having an irregular-shaped collar 69 on one side thereof, are pivotally mounted. Also secured to the member 61 is a member 68, corresponding to each of the bifurcated members, which has oppositely extending projections 73 and 74 serving to direct the movement of the vanes secured to the shaft 46. Disposed in a position central to the extensions 73 and 74 are wedge-shaped projections 75, which in turn are integral with a member 76 secured to the member 61. In order to deflect the operating vanes to one side or the other of the bifurcated members 63 to 67, inclusive, in accordance with the desired code combination of message impulses, a member 78 slideable longitudinally, and having wedge-shaped projections 79 corresponding to the projections 75, is arranged under the control of the operating magnets 29 and 30. 100 As shown in Fig. 1, the member 78 is arranged to be moved in one direction upon the energization of magnet 29 through the medium of the armature 80, and in the opposite direction due to the energization of the operating magnet 30. Thus, upon the energization of these magnets, which magnets will be energized in accordance with the signaling current impulses, the bifurcated members 63 to 67 inclusive will be operated to effect the closure of circuits extending through their associated contacts 82 and 83, or effect mechanical positions or selections. 115

Immediately after the last bifurcated member 63 has been actuated by its operating vane 56, a cam 84 on the shaft 46, is brought into operative relation with a link 86, which is secured to a shaft 88. This 120

shaft 88, serves upon being rotated, to cause the rotation of shaft 89, and consequently the release of shaft 96, forming a part of the printer mechanism.

5 A receiving printer of the character with which a distributor mechanism of the type herein described is especially applicable is disclosed in my copending application, Serial No. 424,372, filed November 16, 1920, 70 and since the above mentioned copending application illustrates and describes in detail the various operations of a receiving printer, it is considered unnecessary to show a complete structure of a receiving printer 15 as applied to the present invention. Obviously, however, a distributor of the character covered by this invention is applicable to types of receiving printers other than that disclosed and described in my above 20 referred to copending application.

Upon the engagement of the cam 84 with the operating link 86, the shaft 88, which is linked with shaft 89, which in turn has secured at one extremity thereof one part 25 of a toggle joint comprising members 90 and 91, as shown in Fig. 8, is rotated through a predetermined angle. By means of a spring 92, which has one end attached to the member 90, and the other to a support 98, the member 90 is thus normally retained in engagement with an adjustable stop screw 93. Rigidly secured to the member 91 of the toggle joint is a block 94, arranged to be revolved about a shaft 97 mounted in 35 the frame 100. Due to the rotation of the shaft 89 and a similar motion of the member 90 of the toggle joint, and due to the manner of connection between the members 90 and 91, a downward movement of the 40 block 94 is effected. The block 94 thereupon moves to a position whereby a stop arm 95, carried by an operating shaft of the receiving printer, is released. The release of the stop arm 95 permits the shaft 96 to be 45 revolved by power communicated thereto through a friction clutch forming a part of the printer mechanism.

Also rigidly secured to the shaft 46 is a cam 85 arranged to operate a link 87, which 50 is also secured to the shaft 88. The position of the cam 85 on this shaft is such that following the rotation of the shaft due to the operation of the link 86, the link 87 is moved in a direction whereby the shaft 88 is rotated in a direction opposite to that caused by the actuation of the link 86 by the cam 84. In this manner the members 90 and 91 of the toggle joint will be restored to their 55 normal position under the action of the spring 92, thereby placing the block 94 in the path of the stop arm 95, which will be arrested upon the completion of its cycle of rotation.

In order to provide the proper time interval between the receipt of the releasing

impulse and the release of the distributing unit B, the release magnet 16 together with the stop arm 12 is arranged to rotate about a bearing secured to the shaft 7. Thus the time interval between the release of the stop arm 12 upon the energization of the release control magnet 16 and the release of the stop arm 27 secured to the shaft 46 may be varied so that the proper relation will exist between the initial impulse and the following or selecting impulses. 75

Fig. 10 illustrates a line circuit to which there is connected a transmitting distributor of the rotary or brush type, and a receiving distributor of the type herein described. 80

The structure illustrated in this figure comprises in general a transmitting distributor 103 consisting of an inner and outer ring over which a brush arm 104 is designed to pass. The outer ring is divided into a plurality of segments which are connected to the contacts of a tape transmitter or any well-known type of transmitter. The brush arm 104 is normally held against rotation by means of a latch 105 which is under the control of a release magnet 106. Upon energization of the release magnet 106, the brush arm 104 is free to make one revolution, power being communicated thereto through a slip friction clutch in a manner well-known. 90

A distributor of the character hereinbefore described, has its operating magnets 29 and 30 connected with the contacts of a receiving relay 107, which has its windings connected in the ratio arms, forming a part of the line conductor 108 extending to the distant station. As in all signaling systems of the type wherein the real line is balanced against an artificial line, the receiving relay is constructed so as to be non-responsive to outgoing impulses, but responsive to incoming impulses. To the contacts on the distributor illustrated in the rectangle 109, there is connected the windings of the operating magnets 110, 111, 112, 113, and 114 of the receiving printer. 105

The operation of the system is as follows: Assume for the sake of clarifying the description that contacts 115, 117 and 119 of the transmitter are closed to connect the corresponding segments of the distributor 103 to a source of battery, and that the distributor arm 104 is released for rotation. Immediately following the release of the distributor arm 104 and the passage over segment 120, an open circuit condition is established whereby the receiving relay 107 at the distant station is caused to reverse the position of its armature. The reversal of the armature of this relay completes an energizing circuit for the release control magnet 16 at that station. Upon the energization of this magnet, the stop arm 12 carried by the sleeve 10 is free to rotate 110 120 125 130

through the friction discs 11 and 18, and after traversing a small angle, cam 19 is made effective whereby switch member 39 is moved to open contact 34 and close contact 33, thereby transferring the circuit extending from the receiving relay 107 to the release control magnet 16, to the operating magnets 29 and 30 of the distributor. Contact 115 for the particular selection being closed, battery is applied to the line 103 upon the passage of the brush arm 104 over the corresponding segment of the distributor whereupon the receiving relay 107 again reverses the position of its armature and establishes an energizing circuit extending from battery, armature of relay 107, contact 121, winding of operating magnet 30, contact 33 and switch member 39, to ground. As previously described, the shaft 46 is released for rotation after the shaft 7 has been rotated through a predetermined angle. Thus the vane individual to the bifurcated member 67 will be shifted upon its continuous rotation to the left-hand side of this member, but since this member had previously been positioned to make contact with its right-hand contact no movement thereof is brought about by the movement of the vane in this manner. Upon the passage of the brush arm over the segment to which the contact 116 is connected, an open circuit condition is established to the line conductor 108 whereby the receiving relay 107 is actuated to open contact 121 and close contact 122. The closure of contact 122 establishes an energizing circuit for operating magnet 29 extending from battery, through the armature of relay 107, contact 122, winding of operating magnet 29, contact 33 of the transfer switch 32, and switch member 39 to ground. The bar 78 carrying the wedge-shaped projections 79 is thereby moved to the left so that upon the rotation of the shaft 46 and the engagement of the operating vane individual to the bifurcated member 66, vane 59 will be deflected to the right of this member so that upon its continued rotation the member 66 is caused to move from its associated right-hand contact to its left-hand contact, thereby opening the circuit of selected magnet 113. As the brush arm 104 continues its rotation and passes over the respective segments of the distributor, the line conditions depending upon whether the transmitter contacts are opened or closed will be altered to in turn effect the energization of receiving relay 107. In the combination chosen contacts 117 and 119 of the transmitter are closed, thereby conditions similar to those described in connection with the transmission of the first selecting impulse will be established, but as in this case the bifurcated members 65 and 63 being already in contact with the right-hand contact, no movement

thereof will be effected. Owing to the fact, however, that contact 118 of the transmitter is open for the particular selection chosen, the bifurcated member 64 will be moved in a manner similar to that described in connection with the movement of the member 66 for causing a similar action to the selecting magnet individual thereto.

From the above description it is apparent that the invention provides a distributing mechanism wherein the electrical impulses are translated into mechanical movements which later effect the closure of electrical circuits. Although the invention has been described in connection with a particular circuit arrangement, it is of course obvious that the mechanism may be applied to other types of equipment without departing from the spirit and scope of the invention.

What is claimed is:

1. In combination, a plurality of members, arranged to occupy one of two positions, means individual to said members for causing their movement, means controlling the deflection of said means to one side or the other of said members for causing their movement in either of two directions, and means responsive to selecting current impulses for controlling the positioning of said second recited means. 95

2. In combination, a plurality of members having the free ends thereof arranged to occupy either of two positions, a rotatable member individual to each of said members for effecting the movement thereof, and means including a single selecting magnet responsive to selecting current impulses for controlling the positioning of said rotatable members. 100

3. In combination, a plurality of members arranged to occupy either of two positions, means individual to each of said members for effecting the movement thereof, a slid-able member having a wedge-shaped projection thereon individual to each of said means, and means for moving said slid-able member, whereby the wedge-shaped projections thereof are made effective to cause the successive operation of said means to selectively operate said members. 110

4. In combination, a plurality of pivoted members having the free ends thereof arranged to occupy either of two positions, a shaft arranged to be rotated, an operating vane individual to each of said members pivotally secured to said shaft, a slid-able member having wedge-shaped projections corresponding to each of said vanes, and means responsive to selecting current impulses for positioning the wedge-shaped projections of said slid-able member in the path of said vanes are positioned with respect to said members upon their rotation. 120

5. In combination, a plurality of pivoted members arranged to occupy either of two 130

- positions, means normally tending to rotate for moving said members about their pivot, electromagnetic means for permitting the rotation of said means, and further means responsive to selecting units for determining the position of said rotatable means with respect to said members and means effective through said further means for selectively operating said members.
6. In combination, a plurality of members having the free ends thereof arranged to occupy either of two positions, a shaft normally tending to rotate, an operating vane individual to each of said members secured to said shaft, electromagnetic means controlling the release of said shaft for rotation, and means operative subsequent to the operation of said electromagnet for determining the position of said vanes on one side or the other of said members and means operative through said vanes for causing the movement of said members to either one of their two positions.
7. In combination, a plurality of members arranged to occupy either of two positions, an operating vane individual to each of said members and normally tending to rotate for effecting the movement of said members, a driving connection through which said vanes are rotated, means common to said vanes for determining the position thereof with respect to said members, means for releasing said driving connections, and means operated subsequent to the release of said driving connection for rendering the means common to said vanes responsive to selecting current impulses.
8. In combination, a plurality of members arranged to occupy either of two positions, an operating vane individual to each of said members and normally tending to rotate for effecting the movement of said members, a driving connection through which said vanes are rotated, means common to said vanes for determining the position thereof with respect to said members, means for releasing said driving connection, and mechanical means operated subsequent to the release of said driving connection for rendering the means common to said vanes responsive to selecting current impulses.
9. In combination, a plurality of members arranged to occupy either of two positions, an operating vane individual to each of said members and normally tending to rotate for effecting the movement of said members, a driving connection through which said vanes are rotated, electromagnetic means common to said vanes for determining the position thereof for releasing said driving connection, and mechanical means operated subsequent to the release of said driving connection for rendering said electromagnetic means common to said vanes responsive to selecting current impulses.
10. In combination, a plurality of members arranged to occupy either of two positions, a shaft normally tending to rotate, an operating vane individual to each of said members pivotally secured to said shaft, a driving connection through which said shaft is rotated, means common to said vanes for determining the position thereof with respect to said members, means for releasing said driving connection, and mechanical means operated subsequent to the release of said driving connection for rendering the means common to said vanes responsive to selecting current impulses.
11. In combination, a plurality of members arranged to occupy either of two positions, a shaft normally tending to rotate, an operating vane individual to each of said members pivotally secured to said shaft for determining the position of said members, a driving connection through which said shaft is rotated, a slidable bar having a wedge-shaped projection individual to each of said vanes, a single electromagnet for selectively positioning said bar whereby said vanes upon being rotated will engage said projections and be positioned on one side or the other of the member individual thereto, means for releasing said driving connection, and means operated subsequent to the release of said driving connection for permitting said shaft to be rotated.
12. In combination, a plurality of members arranged to occupy either of two positions, an operating vane individual to each of said members and normally tending to rotate for effecting the movement of said members, a driving connection through which said vanes are rotated, an electromagnet common to said vanes for determining the position thereof with respect to said members, an electromagnet for releasing said driving connection, a switch, and means operated subsequent to the release of said driving connection for transferring the circuit from said last mentioned electromagnet to said electromagnet common to said vanes.
13. In combination, a releasing unit comprising a shaft normally tending to rotate, means for releasing said shaft, mechanically operated means effective upon the rotation of said shaft, a distributing unit having a plurality of members arranged to occupy either of two operative positions, means individual to said members for effecting their movement, and means rendered effective upon the operation of said mechanically operated means for determining the position of said last recited means with respect to said members.
14. In combination, a releasing unit comprising a shaft normally tending to rotate, an electromagnet for releasing said shaft, mechanically operated means effective upon

- the rotation of said shaft, a distributing unit having a plurality of members arranged to occupy either of two operative positions, and means individual to said members for effecting their movement, and an electromagnet rendered effective upon the operation of said mechanically operated means for determining the position of said last recited means with respect to said members.
15. In combination, a releasing unit comprising a shaft normally tending to rotate, means for releasing said shaft, mechanically operated means effective upon the rotation of said shaft, a distributing unit having a plurality of selectable elements, rotatable means for positioning said elements, a driving connection between the shaft of said releasing unit and said distributing unit, and means rendered effective upon the operation of said mechanically operated means for causing the release of said distributing unit.
16. In combination, a releasing unit comprising a shaft normally tending to rotate, means for releasing said shaft, mechanically operated means effective upon the rotation of said shaft, a distributing unit having a plurality of pivoted members with the free ends thereof arranged to occupy either of two operative positions, an operating vane individual to each of said members for effecting their movement, an electromagnetic means common to said vanes and rendered effective upon the operation of said mechanically operated means for determining the positioning of said vanes with respect to said members.
17. In combination, a releasing unit comprising a shaft normally tending to rotate, an electromagnet for releasing said shaft, mechanically operated means effective upon the release of said shaft, a distributing unit having a plurality of pivoted members with the free ends thereof arranged to occupy either of two operative positions, a shaft normally tending to rotate, an operating vane individual to each of said members pivotally secured to said shaft, and means rendered effective upon the operation of said mechanically operated means for the successively positioning of said vanes with respect to said members.
18. In combination, a releasing unit comprising a shaft normally tending to rotate, means for releasing said shaft, mechanically operated means effective upon the rotation of said shaft, a distributing unit having a plurality of pivoted members with the free ends thereof arranged to occupy either of two operative positions, a shaft normally tending to rotate, an operating vane individual to each of said members pivotally secured to said shaft, means rendered effective upon the operation of said mechanically operated means for causing the release of said shaft, and electromagnetic means rendered effective upon the further rotation of said first recited shaft for determining the position of said vanes with respect to said members.
19. In combination, a plurality of circuit controlling members arranged to occupy either of two positions, means individual to each of said members but distinct therefrom for effecting the movement thereof, and means common to said means and responsive to selecting units for controlling the positioning of said means.
20. In combination, a plurality of pivoted circuit controlling members having the free ends thereof arranged to occupy either of two positions, means individual to each of said members for effecting the movement thereof, and means common to said means and responsive to selecting units for causing the operation of said members through the instrumentality of said means.
21. In combination, a plurality of circuit controlling members arranged to occupy either of two operated positions, a shaft arranged to be rotated, means pivotally secured to said shaft for effecting the movement of said members, and means responsive to selecting current impulses for determining the position of said means with respect to said members.
- In witness whereof, I hereunto subscribe my name this 27th day of October A. D., 1921.
- MERLE P. CHAPLIN.
